UNITED STATES PATENT OFFICE.

EDWIN B. STIMPSON, OF BROOKLYN, NEW YORK.

PUNCHING AND EYELETING MACHINE.

SPECIFICATION forming part of Letters Patent No. 696,211, dated March 25, 1902.

Application filed October 1, 1900. Renewed August 10, 1901. Serial No. 71,636. (No model.)

To all whom it may concern:

Be it known that I, EDWIN B. STIMPSON, a citizen of the United States, residing in the borough of Brooklyn, in the county of Kings 5 and city and State of New York, have invented certain new and useful Improvements in Punching and Eyeleting Machines, of which the following is a specification.

This invention relates to machines adapted 10 to punch the material and set an eyelet in the hole punched; and the object of the invention is to provide a simple machine wherein the punching and setting operations are performed successively, but at one operation of 15 the machine.

In the accompanying drawings, which illustrate an embodiment of the invention, Figure 1 is a side elevation of the entire machine on a relatively small scale and showing the parts 20 in their normal condition of rest. Fig. 2 is a front elevation of the upper part or head of the machine on a larger scale than Fig. 1, also showing the parts in their normal condition of rest. Figs. 3 and 4 are respectively a side 25 and front elevation of the upper part or head of the machine on the same scale as Fig. 2 and showing the parts in the position of setting the eyelet. Fig. 5 is a plan of the supporting-plate for the material. Fig. 6 is a 30 cross-section of the eyelet-set and its guideway. Fig. 7 is a sectional view of the head of the toggle-operating rod. Fig. 8 is a view of the eyelet-set, detached and partly in section. Fig. 9 is a fragmentary view illustrating a 35 construction of the arm 19, different somewhat from that seen in the principal views.

The general construction of the machine as herein shown and its operation will be briefly described.

40 The head of the machine is mounted on a column or base, at the lower part of which is an operating-treadle to be depressed by the foot. The eyelets are in an oscillating box or magazine carried on the upper end of an inclined sliding eyelet-track. On the head is a bed or plate to support the material to be punched and to receive the eyelets, and the punch is mounted in a guide above and is depressed in punching. The eyelet-set is guided 45 below and moves upward in setting, being operated by a special toggle device from the

treadle. As the eyelet-set moves upward the punch is first driven downward through the material and then retracted. Then the set takes an eyelet from the track and moves the 55 latter back out of its path, and then in its continued upward movement the set swings laterally an arm above, which carries the punch and the eyelet setting or clenching anvil, shifting the punch to one side and putting the anvil into alinement with the upwardly-moving set. The termination of the movement of the set clenches or rivets the eyelet.

1 is the head of the machine, which is 60 mounted on the column 2. On the column is fulcrumed the treadle 3, which may have a counterweight 4 and a retracting-spring 5. On the head is secured a supporting-plate 6, and in a vertical guideway in the head below 70 is mounted the eyelet-set 7, adapted to move up and down. To operate this set, a rod 8, coupled at one extremity to the pedal, is coupled at the other extremity to the knuckle of a toggle consisting of two links 9 and 9^a. The 75 lower link 9 is coupled to the stationary head 1, and the upper link 9^a is coupled to the eyelet-set 7.

10, Fig. 1, is the eyelet box or magazine, mounted to oscillate or rotate on the upper 80 end of the eyelet-track 11, this track being secured to a cylindrical slide 12, mounted in guides 13 on the head 1. On the lower end of this slide is a stud or pin 14, which engages a cam-slot 15 in a rocker 16, mounted on the 85 head 1, and when the set 7 is moved upward a stud 17 thereon engages the rocker, rocks it, and moves the track 11 back out of the way. However, on the upper end of the eyelet-set 7 is a pin 7^a, which as the set rises 90 passes upward through the terminal eyelet in the track, so as to engage and hold it, and as soon as this engagement is effected the stud 17 engages the rocker 16 and moves the track 95 back out of the way.

Mounted to swing laterally with a pin 18, forming a vertical hinge axis, is an arm 19. This arm carries at its free end the clenching-anvil 20, which is fixed or stationary, and the punch-carrier 21 and punch 22, secured 100 therein. The punch-carrier plays in a guideway in the arm, is normally alined with the

eyelet-set, and is operated by a bent lever 23, fulcrumed at y on the arm 19. The pendent arm 23^a of the bent lever 23 is adapted to be acted on by the upper arm of a lever 24, fulcrumed at z on the head or frame of the machine, and the lower arm of the lever 24 is in the path of a stud 25, which projects laterally from the head of the rod 8, as seen in Fig. 4. This stud is so placed that it engages the lever 24 and through it and the bent lever 23 actuates the punch at the first part of the punching and setting operation. The lower arm of the lever 24 is bent outward and downward, so as to form a shoulder at 24^a, and the stud 25 impinges first on the lever below this shoulder. Then as the parts move it slides up and disengages itself from the lever at this shoulder and at the completion of the punching operation, allowing the punch-carrier to be retracted by its spring. (Indicated in dotted lines in Fig. 2.) Such retracting-springs are common in punches and do not require special illustration. Any spring will serve. As the eyelet-set 7 continues to move upward and immediately after the punch is retracted a stud or pin 26, projecting laterally from the eyelet-set, engages a cam 27 on an arm 28, fixed on the hinge-pin 18, and displaces said cam and arm laterally, thus swinging laterally the arm 19 and bringing the anvil 20 into alinement with the ascending eyelet-set 7. As the eyelet-set continues to move upward, and immediately after the anvil has been shifted into alinement, the pin 7^a in the set engages the terminal eyelet in the track, and the latter is moved back out of the way by the stud 17 and rocker 16. The ascending eyelet-set carries the eyelet up and inserts it from below into the hole punched, pressing it upward, finally, and clenching it on the anvil 20. When the operation is thus completed, the spring 5 retracts the parts.

It may be explained that the rocker 16 is of such shape that when the set 7 moves upward the stud 17 engages a projecting part thereof, rocks the rocker, and passes on, and in the downward movement of the set the stud 17 engages another arm on the rocker and rocks it back again. Thus the rocker is moved in both directions positively by the stud 17.

It may be noted here that in the construction shown the eyelet-box 10 is oscillated by a link 29 (which couples it loosely to the head 1) whenever the box is moved to and fro by the displacement of the track. This is a known device and has no special relation to the present invention.

The stud 25 in the head of the rod 8 is beveled in the manner of a latch-bolt, and said stud is backed by a spring, so that it may be pressed in as it wipes over the lower end of the lever 24 in going back. This feature is illustrated in the detail view, Fig. 7.

65 The stud or pin 7^a in the upper end of the eyelet-set 7 is adapted to be pressed back or in when it impinges upon the central nipple

of the anvil 20 in clenching the eyelet. This feature is illustrated in Fig. 8, wherein 7^b is the spring behind the pin. 70

The punch 22 is a die-punch and when driven down enters a lower die 30 on the arm 19. The supporting-plate 6 is slotted, as indicated in Fig. 5, to permit the die 30 to play when the arm 19 is displaced laterally. The 75 lateral displacement of the arm 19 displaces the lever 23 also; but this displacement is not enough at the point of contact of the lever 24 with the pendent arm 23^a to disengage them.

The cam 27 is of such a form that when 80 displaced by the stud 26 the latter holds the arm 19 displaced until the eyelet-set 7 descends or is retracted. The arm 19 is brought back to its normal position by a leaf-spring 31. (Seen in Fig. 2.) This is a simple flat 85 spring secured to the head 1, with its free end bearing on the arm 19. Any known spring construction may be employed to effect this object.

In the principal figures the arm 19 is shown 90 in its simplest form with two integral jaws or branches, the upper branch carrying the punch and the lower branch the die 30; but the construction seen in Fig. 9 is sometimes preferred. In this view the lower branch 19' 95 is not integral with the upper branch, but is mounted on the pin 18, so that when a set-screw 19" or other means for securing it is loosened the branch 19' may be swung around to one side, thus affording ready access to 100 both the punch and die for removal or substitution. For example, the die-punch may be substituted by a cutting-punch and the die 30 by a cutting-plate.

The employment of the cylindrical slide 12 105 effects an important economy in the construction, as it may be turned and the guides or bearings therefor bored in the guide-lugs 13 on the head. To prevent the slide from rotating or rocking in its bearings, a flattened 110 face 12' is formed on it, and a block 13' is screwed onto the lug 13 to bear on said face. Preferably there will be a flattened face and block at each lug 13. The eyelet-track 11 is secured by screws to a long support or carrier 11', and this carrier is secured to the slide 12. 115

Having thus described my invention, I claim—

1. A punching and eyelet-setting machine, 120 comprising a laterally-displaceable punch and clenching-anvil, a displaceable eyelet-track, an eyelet-set, mechanism for operating said punch and eyelet-set conjointly, and mechanism actuated by the moving eyelet-set for displacing the punch and eyelet-track and for putting the anvil into alinement with the set, all of said operations being effected during one operation of the machine. 125

2. A punching and eyelet-setting machine, 130 comprising a laterally-displaceable die-punch and die, and a clenching-anvil abreast of and displaceable with said punch, a displaceable eyelet-track, a reciprocating but not laterally-

displaceable eyelet-set, mechanism for operating said eyelet-set and punch conjointly, and mechanism, actuated by the moving eyelet-set for laterally displacing the punch and 5 clenching-anvil, and displacing the eyelet-track, at one operation of said eyelet-set.

3. In a punching and eyelet-setting machine, the combination with the supporting-plate for the material, a die-punch, a clenching-anvil situated above the material, a laterally-swinging arm carrying said punch and anvil, and means for supplying eyelets, of a reciprocating eyelet-set below the material and normally alined with the punch, means 10 for operating said eyelet-set, and punch conjointly, and means actuated by the upwardly moving eyelet-set for putting said clenching-anvil into alinement with the eyelet-set, at 15 one operation of the latter.

4. In a punching and eyelet-setting machine, the combination with the eyelet-set, the anvil, the toggle-links 9 and 9^a, connected together at the knuckle, and to the said eyelet-set and a stationary part, at their respective 20 ends, the treadle, and the rod 8, connecting said treadle with the knuckle of the toggle, of the punch, and mechanism between said rod 8 and the punch whereby the former operates the latter conjointly with the eyelet-set.

5. In a punching and eyelet-setting machine, the combination with the punch-carrier and punch, the bent lever 23, for operating same, the intermediate lever 24, having a 25 shoulder 24^a, the eyelet-set, the toggle connected therewith, and the treadle, of the rod 8, provided with a movable pin 25, in the 30 form of a latch-bolt, adapted to engage the lever 24 to actuate the punch conjointly with 35 the eyelet-set.

6. In a machine for the purpose set forth, the combination with the laterally-movable arm 19, means for returning it to its normal position after it has been displaced, the clenching-anvil carried by said arm, the punch and 45 lower die carried by said arm, the eyelet-set, and means for operating said punch and eyelet-set, of means whereby the moving eyelet-set displaces the arm 19, said means comprising a stud on the eyelet-set and a cam, 50 which is in the path of said stud and movable with said arm.

7. In an eyelet-setting machine, the combination with the inclined,slidable eyelet-track, and the eyelet-box or magazine mounted on 55 the same, of the rocker 16, having in it a slot 15 engaged by a stud 14 on the slide of the track, and the eyelet-set 7, having a stud 17, which engages said rocker and rocks it when the set ascends, substantially as and for the 60 purpose set forth.

8. A machine for the purpose set forth, having the movable arm 19, comprising two non-integral branches, the lower branch, 19', being capable of lateral displacement for facilitating the removal of the punch and die. 65

9. In a machine for the purpose set forth, the combination with the head, having bearing-lugs with cylindrical bearings and a block 13', of the cylindrical slide 12, having a flattened face 12', engaged by the block 13', the carrier secured to said slide, and the eyelet-track secured to said carrier. 70

In witness whereof I have hereunto signed my name, this 25th day of September, 1900, in 75 the presence of two subscribing witnesses.

EDWIN B. STIMPSON.
